UNITED STATES PATENT OFFICE.

EDGAR C. WILEY, OF LYNCHBURG, VIRGINIA, ASSIGNOR TO COMBUSTION REGULATOR CO., INC., OF LYNCHBURG, VIRGINIA, A CORPORATION OF VIRGINIA.

DRAFT REGULATOR.

Application filed March 25, 1919. Serial No. 285,034.

To all whom it may concern:

Be it known that I, EDGAR C. WILEY, a citizen of the United States, residing at Lynchburg, in the county of Campbell and State of Virginia, have invented new and useful Draft Regulators, of which the following is a specification.

This invention has reference to draft regulators of the type shown and described in Letters Patent #1,208,432, granted to me on December 12, 1916, and its object is to avoid the effects of the distillation of the volatile gases at a rapid rate by highly incandescent fuel when there is an insufficient supply of air to complete the combustion of the gases, such conditions sometimes occurring when the automatic damper cuts off the air supply beneath the grates for purposes of checking combustion without at the same time admitting a sufficient supply of air over the fuel bed to complete the combustion of the gases. Even though such an objectionable condition lasts but a short time the incompletely burned gases are driven off in large quantities and cause a quick deposition of thick coatings of soot within the boiler flues and on the heat absorbing surfaces.

With the present invention supplementary air is introduced into the combustion chamber in synchronism with the movement of the main air supply damper cutting off the supply under the grate, whereby the gases reaching the combustion chamber are met by a sufficient quantity of air to afford perfect combustion and thus avoid depositions of soot.

The invention contemplates the provision of a wall having many air passages through it, which for convenience may be termed a perforated wall, whereby to admit a limited quantity of fresh air over the top of the fuel bed to aid in the combustion of gases arising from the fuel bed after the supply of fresh air underneath the grates has been closed or very nearly closed by the movements of the automatically controlled damper.

With the structure shown and described in the aforesaid Letters Patent, and also with other automatic boiler draft controls, there occurs a time just after the damper admitting air to the ash-pit has closed when the fuel bed or charge is left in a highly incandescent state, thereby distilling volatile gases at a rapid rate without there being any

supply of air to complete the combustion of the gases.

The supplementary air supply is so designed as to be insufficient in itself for checking purposes, this being taken care of by an air check admitting air over the fire bed as in the aforesaid Letters Patent, but the supplementary air is arranged to cause the combustion of gases produced when the air draft to the grate has been closed or has very nearly reached the closed position, and while the supplementary air may serve to some extent for checking purposes, its main purpose is to provide for the interval between the time when the air is cut off from the grate and the time when checking air is admitted to the combustion chamber.

The invention will be best understood from a consideration of the following detailed description taken in connection with the accompanying drawing forming part of this specification, with the understanding, however, that the invention is not confined to any strict conformity with the showing of the drawing, but may be changed and modified so long as such changes and modifications mark no material departure from the salient features of the invention as expressed in the appended claims.

In the drawing:—

Figure 1 is a central vertical front to rear section of a furnace embodying the invention.

Figure 2 is a similar view showing a somewhat modified form of the invention.

Referring to the drawing, there is shown a portion of a furnace 1, which may be taken as typical of a heating furnace adaptable for use in a vapor heating system, such, for instance, as is customarily employed in residences and other buildings, although the invention may be used wherever regulation of the kind it provides is desirable. The furnace shown has the usual ash-pit 2, grate 3, combustion chamber 4 and smoke pipe connection 5, none of which need be described in detail.

At the rear of the ash pit there is a duct 6 connected to another duct 7 which may be formed in a casting 8 containing still other ducts 9 and 10. These ducts 7, 9 and 10 are arranged at the rear of the furnace and have openings or ports 11, 12 and 13 opening to the atmosphere, and in the particular show-

ing of the drawing, these openings or ports are grouped together so as to be closely adjacent. This is because the openings or ports may then be controlled by a single convex damper plate 14, the ports 11, 12 and 13 being correspondingly concave in the particular showing of the drawing, the construction being similar to that shown in the aforesaid Letters Patent.

10 The plate or damper 14 is mounted in supporting arms 15 to turn on an axis corresponding to that of the curvature of the plate 14 and this damper plate is counterbalanced by a weight 16. The damper is controlled by a link 17 fastened to an arm 17^a on the damper plate, and this link is in turn under the control of a lever 18 engaged by a pressure responsive device 19 movable by boiler pressure, or any suitable 20 controlling means adapted to steam or hot water boilers, may be employed. The parts so far described, with respect to the draft regulator, may be such as are shown and described in the aforesaid Letters Patent and 25 may operate in like manner thereto, so that no extended description of the construction or operation is herein necessary.

15 The ducts 9 and 10 are divided by a wall or plate 20 having numerous passages 21 therethrough which may be, although are not necessarily, in the form of perforations and are made relatively small. The duct 9 communicates with the fire chamber 4, through another duct 22, and in the structure shown in Figure 2 the duct 10 also communicates with the smoke flue 5 by way of a passage 23. Whether in accordance with one or the other of these arrangements, the duct 10 with its inlet port 13 and the plate 20 with the passages 21 therein form an air inlet for the admission of air to the duct 22 leading to the combustion chamber, which air inlet is supplemental to the duct 9 with its inlet port 12.

20 With the device of the invention, when the fire box 4 is filled with fresh fuel, such fuel heats up rapidly and the steam pressure, or water temperature in a hot water boiler, is brought up to a point where the automatic damper regulator causes the movement of the damper plate 14 to an extent to practically close the duct 7 and then the duct 10 will begin to open to the atmosphere thereby admitting air to the duct 10. Such air is 25 drawn through the holes in the perforated plate 20 into the duct 9 and from thence through the duct 22 into the fire chamber and over the bed of fire where such supplementary air will unite with the gases arising from the fuel bed. As the damper advances so as to entirely close the duct 7 and completely shut off the air underneath the grate 3, such secondary or supplementary air is sufficient to complete the combustion 30 of gases being distilled from the fuel bed

purely because of the intense heat of such fuel bed. If the boiler pressure, or water temperature, continues to increase there occurs a further movement of the damper plate 14 which, after an interval of time begins 70 to and may ultimately fully open the port 12, thus admitting fresh air in checking quantities as in the device shown in the aforesaid Letters Patent, and this checking function may be augmented by air entering 75 through the port 13 and finding its way through the passages 21 into the flue 9.

80 In the structure shown in Figure 2, the opening of the port 13 admits air to the smoke inlet or flue and supplementary air 80 through the passages 21 to the space in the fire chamber above the bed of coal. So far as the perforated wall 20 is concerned its function is similar in the structures shown in both Figures 1 and 2. Aside from this 85 the structures of Figures 1 and 2 are similar to the structures set forth in the aforesaid Letters Patent, that is, in Figure 1 there is shown a two-phase construction admitting air to the ash-pit and then to the fire chamber as the ash-pit air is cut off, for firing 90 and checking purposes, and in Figure 2 there is shown a three-phase construction, in which air is admitted to the ash-pit, then to the smoke flue and then to the fire chamber, the admission of air to the smoke flue 95 and fire chamber being for checking purposes and occurring in the order named.

90 The air reaching the fire chamber by way of the perforations 21 first serves for combustion purposes with respect to the gases evolved from the fuel after the main supply of air is nearly or fully cut off, and then as the checking air is admitted through the port 12 the supplementary air admitted 100 through the perforations 21 has the effect of increasing the checking air at the beginning 105 of the checking operation with respect to the fire chamber. However, the prime purpose 110 of the perforated wall 20, which wall may be replaced by any means answering the same purpose, is to automatically supply supplementary air to cause the complete combustion of gases distilled from the fuel 115 and in the unburned state reaching the heat absorbing surfaces because of the lack of air supply through the grate due to the closing of the port 11.

120 What is claimed is:—

1. A draft regulator for furnaces comprising a draft duct leading to the ash-pit of the furnace, and air ducts for delivering air to the combustion chamber, the second-named ducts being joined through a perforated dividing wall, and a damper controlling the inlets to the ducts in succession. 125

2. A draft regulator for furnaces having three ducts opening to the atmosphere and the ends remote from the furnace and there in adjacent relation, one duct leading to 130

- the ash-pit of the furnace, another duct leading to the combustion chamber of the furnace, and a third duct communicating with the second-named duct through a plurality of relatively small openings, and a damper common to the ducts and movable with relation thereto in a direction to close the duct to the ash-pit, open one of the other ducts to cause air to flow through the relatively small openings into the second-named duct and through the latter to the fire chamber and finally open the third duct to the fire chamber to supply air thereto in checking quantities.
- 15 3. A draft regulator for furnaces provided with draft and other air ducts all communicating with the atmosphere at one end and there provided with ports in close relation, two adjacent ducts having a perforated wall between them whereby air may reach one of the ducts through either or both of their ports, and a damper movable across the ports in succession.
4. A draft regulator for furnaces provided with draft and other air ducts all communicating with the atmosphere at one end and there provided with ports in close relation, those ducts other than the draft duct communicating through a perforated wall with one of the ducts in turn communicating with the fire chamber of the furnace and the other duct with the smoke flue of the furnace, and a damper movable across the ports in succession, whereby air may be admitted to the ash-pit for combustion purposes, air may be admitted to the smoke flue and fire chamber for checking purposes, and supplementary air may be admitted to the fire chamber for combustion purposes.
- 40 5. A draft regulator for furnaces comprising an air duct leading to the ash-pit of the furnace and at the end remote from the ash-pit having a port communicating with the atmosphere, another duct adjacent to the first-named duct and leading directly into the fire chamber of the furnace and at the end remote from the fire chamber provided with a port leading to the atmosphere and closely adjacent to the first-named port, and a third duct on the side of the second duct remote from the first-named duct and divided from the second duct by a perforated wall, said third duct having a port adjacent to the second-named port and leading to the atmosphere, and a damper movable in order over the ports, said damper being of a size and having a range of travel to wholly cover the second-named port and simultaneously cover the major portion of both the other ports.
- 55 6. A draft regulator for furnaces having ducts with adjacent ports leading to the atmosphere, two of the ducts having a division wall between them provided with numerous relatively small perforations, and a damper movable across the ports to open or close them in order, one of the ducts leading to the ash-pit of the furnace and the other ducts communicating with the fire chamber of the furnace, one directly and the other through the perforated wall.
7. A draft regulator for furnaces having a duct leading to the ash-pit of the furnace and at the end remote therefrom having a port leading to the atmosphere, another duct leading to the fire chamber of the furnace and at the end remote from said fire chamber provided with a port leading to the atmosphere and closely adjacent to the first-named port, and a third duct separated from the second-named duct by a wall provided with numerous relatively small perforations, through which the third duct communicates with the second duct and by the latter to the fire chamber of the furnace, said third duct leading into the smoke flue of the furnace and having a port opening to the atmosphere adjacent to the second-named port, and a damper movable into controlling relation to the ports and of a size and extent of travel to open or close the ports successively with one or more of the ports always in communication with the atmosphere.
8. A draft regulator for furnaces having a duct leading to the ash-pit of the furnace and at the end remote therefrom having a port leading to the atmosphere, another duct leading to the fire chamber of the furnace and at the end remote from said fire chamber provided with a port leading to the atmosphere and closely adjacent to the first-named port, and a third duct separated from the second-named duct by a wall provided with numerous relatively small perforations, through which the third duct communicates with the second duct and by the latter to the fire chamber of the furnace, said third duct leading into the smoke flue of the furnace and having a port opening to the atmosphere adjacent to the second-named port, and a damper movable into controlling relation to the ports and of a size and extent of travel to open or close the ports successively with one or more of the ports always in communication with the atmosphere.
9. A draft regulator for furnaces comprising an air duct leading to the ash-pit of the furnace and at the end remote from the ash-
